CARTRIDGE LOADER

Elmer Lovell Smith, Longmeadow, and Carlton Wetsel, Springfield, Mass., assignors to Package Machinery Company, Springfield, Mass., a corporation of Massachusetts

Application April 30, 1943, Serial No. 485,182

10 Claims.

(Cl. 86—47)

This invention relates to machines for filling clips with cartridges and has for its object the organization and combination of parts for such a machine as will be wholly automatic in its action, of relatively simple construction, efficient, certain and economical in operation; and which will perform its function of filling said clips at a high rate of speed.

The particular embodiment of the invention hereinafter described is a machine designed for the filling of cartridge clips which are used in the well known Springfield rifle. This type of clip is adapted to be filled from either end with a stack of five cartridges in a single row. It is formed with a rigid base, slightly curved, and having comparatively low side walls within which is secured a spring tensioned member separate from the clip base to create pressure against the base ends of the cartridges and hold them securely against the inturned edges of the clip side walls with a self-sustaining grip. Consequently, in filling said clip with its full complement of cartridges it becomes necessary to force the cartridges in between the inturned edges of the clip side walls and the spring-tensioned sub-base member held within the clip base.

A fully charged clip will contain five cartridges arranged in a single row. In the operation of the filling machine the cartridges should be guided into a pocket and held firmly in perfect alignment in said pocket while the clip is forced over their ends simultaneously to bind them together. When the clip has been assembled with the cartridges the machine will bend retaining lugs at the extreme ends of said clip in against the base ends of the cartridges and confine them to the clip and make out of this assembly a single packet or unit.

In its preferred form my machine is designed to perform the several operations necessary for the filling of such a clip, successively at several stations spaced apart. Cartridges are fed from chutes adjacent a moving carrier into a plurality of pockets within said carrier. The moving carrier may take various forms such as a turret drum, an endless chain, or as here shown, a Ferris type of rotating wheel with a plurality of pockets disposed radially about its periphery for being carried past the aforesaid stations adjacent said moving carrier. The functional objective of the design is the provision in effect of a continuous production train which will comprise various co-operating mechanisms at the several stations and which will require for its successful operation merely a continuous supply of clips and car-

tridges at the infeed end and the carrying away of filled clips at the discharge end.

The several advantages of the invention will become apparent from the following description taken in connection with the accompanying drawings which show the preferred embodiment thereof, and in which

Fig. 1 is a partial side view of the machine illustrating the location of the clip chute and pusher mechanism in relation to the main pocket wheel and its discharge mechanism, with the pocket wheel cover removed;

Fig. 2 is a fragmentary view of a portion of the pocket wheel showing the next step in filling the pockets of the wheel;

Fig. 3 illustrates the drive mechanism pertaining to the several parts shown in Fig. 1 and mounted inside the main frame;

Fig. 4 is a partial side view of the machine with the cover closed upon the main pocket wheel as when the machine is in continuous operation;

Fig. 5 is a partial end elevation, with parts broken away, of the mechanism shown in Fig. 4.

Fig. 6 is a fragmentary plan view of the cartridge guides above the main pocket wheel with certain parts broken away;

Fig. 7 is a partial horizontal section taken through one of the pockets of the main pocket wheel at the clip mounting station of operation;

Fig. 8 is a fragmentary side elevation of the clip chute;

Fig. 9 is a detail view taken on line 9—9 of Fig. 8 showing means for guiding the clips;

Fig. 10 is a detail view taken on the line 10—10 of Fig. 8 also showing clip guiding means;

Fig. 11 is a detail taken on line 11—11 of Fig. 8 at the upper surface of the pusher and removable clip guide;

Fig. 12 is a partial detail taken substantially on line 12—12 of Fig. 11 to illustrate the manner in which the clip pusher acts against the metal clip portion and not the spring mechanism of said clip;

Fig. 13 is a partial side elevation, with parts broken away, of the main pocket wheel at the clip mounting station and with parts broken away from the lowermost portion of the clip chute so as to expose the pusher;

Fig. 14 is a fragmentary view of the cover to the main pocket wheel, as shown in Fig. 4, showing that portion of said cover with parts mounted for performing the last operation on the clip for securely holding the cartridges in place; and

Fig. 15 shows an end view of the cartridges and clip combined to form a single packet or unit.

Referring more particularly to the drawings it will be understood that the machine will comprise a suitable supporting frame, generally indicated at 1. Upon this frame there is mounted for step by step operation a pocket wheel 2, its rotating supporting shaft being indicated at 3.

Referring to Fig. 3, the drive shaft 4, which is driven by any suitable means, has mounted upon it gear 5 which meshes with large gear 6 and in turn drives shaft 7, supported by frame 1, and upon which is mounted a crank 8 (Fig. 1) connected by a link 9 to a sliding member 10 supported by rod 11 mounted in suitable supporting bearings 12 comprising part of a bracket 13. This bracket carries upon itself a guide member 14 suitably mounted to be straddled by a forked portion 15 of sliding member 10 so as to keep pusher 16, which is mounted on the sliding member, in proper alignment with certain pockets of the pocket wheel and the clip chute. Horizontal adjusting means of pusher 16 is provided by set screw 17 with locking means 18 to hold it in proper adjustment.

A sprocket 19 on shaft 7 drives chain 20 which in turn drives sprockets 21 and 22 continuously (Fig. 3). Sprocket 21 is fastened to shaft 23, journaled in the main frame, and carries a Geneva crank 24 which turns continuously. Roll 25 on said crank engages grooves 26 of the Geneva 27 as the locking means 28 is disengaged from recess 29 so as to allow the Geneva to turn. Geneva 27, being secured to the pocket wheel supporting shaft 3, thus turns said pocket wheel 2 in the direction of arrow (Fig. 3) in a step by step motion as is well known in the art.

Shaft 30 carries upon it escapement actuating cams 31 and 32 on the inside of main frame 1, and on the outside this shaft is extended to support discharge belt pulley 33 upon which is a discharge belt 34 which travels continuously to carry away filled clips to be packed for shipment or immediate use. Stud shaft 35 supported by frame 1 carries bell cranks 36 and 37 respectively. Roll 38 on bell crank 36 engages cam 31 while roll 39 is actuated by cam 32 for operating the cartridge escapements in the feed chutes.

Shaft 40, supported by bracket 41 on main frame 1, has secured to it a member 42 which carries escapement 43 and which projects into cartridge chute indicated generally at 44 to hold or release cartridges in proper timed relation with the pockets of pocket wheel 2 as it is rotated step by step. Shaft 40 has an arm 45 (Fig. 3) which is connected by adjustable link 46 to bell crank 36. Springs 48 and 49 tend to keep pin 50 in the uppermost portion of radial slot 51 in block 52 on link 46. When cam 31 contacts roll 38 so as to release escapement 43 from under cartridges C, which have been aligned and fed into chute 44 by any suitable automatic means not described, the first movement of pin 50 carried by bell crank 36 will be of lost motion when suddenly it will come to the end of radial slot 51 and therefore jerk link 46 and turn shaft 40 so as to withdraw escapement 43 rapidly and cause cartridges to drop suddenly and vertically into the empty pocket such as R awaiting them in pocket wheel 2. The same procedure will be carried out in operating escapement 55 which controls the movement of cartridges previously fed automatically or otherwise into a second chute indicated generally at 56 for movement into pockets in pocket wheel 2. Cam 32 will contact roll 39 on bell crank 37 and cause link 57 to jerk lever 58 and turn shaft 59 rapidly and

therefore move escapement 55 out from under cartridges stored in chute 56 and cause them to drop suddenly and vertically into the empty pocket awaiting them in pocket wheel 2, the same as cartridges in chute 44 were controlled. 5 By securing cams 31 and 32 on shaft 30 in a position 180° apart from each other, the escapements 43 and 55 are caused to work alternately. The escapements working alternately will fill alternate pockets of the pocket wheel.

In Fig. 1 escapement 55 has just stopped cartridges from dropping and pocket P has been filled. Escapement 43 is holding cartridges from dropping and pocket wheel 2 is now ready to turn immediately. Pocket wheel 2 will be turned in the direction of arrow (Fig. 1) by Geneva crank 24 previously described. Pocket S was filled and cartridges have been held back by escapement 43 previous to filling pocket P before pocket wheel was moved to the position shown in Fig. 1, and now said pocket S rests at an intermediate position between the two filling stations.

In Fig. 2, pocket wheel 2 has been moved and stopped with pocket Q in under escapement 43 and pocket S is under escapement 55. Escapement 43 has allowed five cartridges to drop into pocket Q and is now holding the remainder in chute 44. Escapement 55 is still holding cartridges in chute 56 until pocket wheel has been moved and stopped again with pocket R directly underneath and at that time escapement 55 will be withdrawn and the pocket R will be filled, therefore completing the cycle. Therefore we have escapements 43 and 55 working alternately to fill alternate pockets in pocket wheel 2 which gives more time for filling chutes 44 and 56 with cartridges and assuring a continuous supply to the escapements so that the machine will continue to run accurately at its most efficient speed.

40 From the cartridge filling stations just described, the pocket wheel moves step by step until the cartridges in each successive pocket come in alignment intermittently one after the other with their clip which has been fed into the clip chute and has dropped down in front of the pusher 16 whose reciprocating action has been previously described, and is timed so as to provide one clip for each set of five cartridges held in each pocket of the pocket wheel 2.

45 In feeding these cartridges to the several pockets in the pocket wheel it is essential to have the cartridges guided in perfect alignment so that each cartridge will be grasped by the clip when it is pushed over their base ends at the clip attaching station, as shown in Fig. 7, and which will be described later.

50 As shown more particularly in Fig. 6, the cartridge chute 44 is made up of a pair of rails serving as front guides 44' and a pair of rails serving as rear guides 44''. Similarly the chute 56 comprises a pair of front guides 56' and a pair of rear guides 56''. Front guides 44' and 56'', shown as in the foreground in Fig. 6, guide the base ends of all cartridges on their way down to the escapements 43 and 55 respectively. The rear guides 44'' and 56'' are provided with bevel surfaces 44b and 56b respectively. The shoulders of the cartridges slide against these bevel surfaces on their way into the pocket wheel, end play being kept to a minimum by end guides 60 (Figs. 4 and 5) supported from guide brackets 61 mounted on cover 62, shown in closed position in Fig. 4.

55 A cylindrical housing 65 encloses the periphery of the pocket wheel 2. T-slots 66 and 67 provide

openings in the housing 65 to receive the cartridges and their escapements 43 and 55 as shown in Fig. 6. The cover 62 is closed and fastened by wing nut 68 while the machine is in operation. A hole 69 in cover 62 allows shaft 3 and nut 63 to protrude.

The pocket wheel 2 comprises a solid hub portion 68' securely fastened to supporting shaft 3 which is rotated step by step as previously described. Secured to hub 68' by screws 69' are two face plates 70 and 71. These two plates 70 and 71 are slotted sixteen times to provide pockets for receiving the cartridges and carrying them to their successive stations for the application of the clip and their ejection as a unit onto the discharge belt which carries them from the machine. At the bottom of these several pockets is provided a hardened block 72 to withstand the dropping of the cartridges into place and to provide a tapered seat which corresponds to an opposed tapered portion 73 of housing 65, and conforms exactly to the shape of the group of five cartridges as they are held firmly in alignment for the application of the clip 66 over their base ends as shown in Fig. 7.

As described before, the cartridges are guided by bevel portions 45b and 56b on guides 44' and 56' respectively and by end guides 60. When they are transferred into the pocket wheel 2 their guiding surfaces then become the beveled edges 75 of pocket slot in inner face plate 71 and edges of the pocket slot in outer face plate 70 of the pocket wheel, and the inner surface 76 of the cover 62 serves as an end guide.

As the pocket wheel stops with the cartridges at the clip receiving station, as shown in Fig. 7, the ends of the cartridges ride up onto a spring-pressed plate 77 which assures the abutment of their shoulders against the beveled edges 75 of the pocket slot in plate 71 by pushing against them simultaneously. Plate 77 is supported by two plunger type bolts 78 which are both pressed inwardly toward the pocket wheel by springs 79 housed in recesses 80 and 81 in member 82 which is secured to the front of cover 62 by bolts 83 as shown in Fig. 4. Nuts and lock nuts 84 of the bolts 78 prevent plate 77 from extending too far in toward the pocket wheel 2 when no cartridges are against it. Adjustment of this plate 77 may be accomplished with the nut and lock nut arrangement.

With the pocket wheel stopped at the clip applying station and the cartridges held firmly in place in the pocket wheel with pressure plate 77 holding their base ends in proper alignment, they are now ready to receive their supporting clip which, when installed, will tie them together into one compact unit.

The clip chute 85 (Fig. 8) is constructed of a front plate 86 and rear guide pieces 87 held in spaced relation with each other by spacers 88 at the upper end of the chute and secured by cap screws 89 to a supporting pad 90 projecting from pocket wheel housing 65. This chute is constructed to give the clips sufficient room to drop vertically and pile up upon themselves. The shape of the rear guide pieces 87 (Fig. 9) conforms generally as at 91 to the shape of the upturned sides 92 of the clip 66 and grooves 94 on each end have been provided for the free movement of the retaining lugs 95 at each end of the clip. The bottom portion 96 of the clip is slightly curved to conform to the general shape taken by the

base ends of the cartridges when they are held firmly together as in Fig. 7.

At the lower end of the clip chute (Fig. 10) a lower clip guide 98 in a solid piece replaces the upper guides 87 at the top of the chute. A beveled surface 99 of this lower guide 98 directs the clips toward the front plate 86 thereby giving them less leeway for free movement so as to align them at the bottom of the clip chute in position to be engaged by the pusher 16.

At the bottom of the chute and towards the front, a removable clip guide 100 is held in place by an L-shaped clamp 101 (Fig. 7). This clamp 101 is freely mounted upon pocket wheel cover hinge pin 102 for vertical movement thereon. A tongue 103 on clamp 101 engages a groove 104 in the end of removable guide 100 (Figs. 7 and 11). A winged nut 105 threaded into clamp 101 is tightened to secure removable clip guide 100 in place. Hinge pin 102 serves as a fulcrum as winged nut 105 is tightened and presses tongue 103 of clamp 101 against groove 104 in removable guide 100 to hold it securely in place.

Should a clip become lodged for any reason at the bottom of this chute, or a faulty clip be disconnected in the chute, lower clip guide 100 may be removed by loosening winged nut 105 and sliding clamp 101 down hinge pin 102 until tongue 103 has disengaged groove 104 in said lower guide 100. Guide 100 may then be pulled forward from out of the notch 110 which is formed between the lower end of guide 98 and the flange portion 111 of supporting pad 90 (Fig. 8). In reassembling, removable guide 100 is set into place and clamp 101 is slid up the hinge pin 102 until it strikes a collar 103' which is fastened onto cover hinge pin 102. At this position, winged nut 105 is securely tightened and the clip chute is made ready for guiding and dispensing clips again.

40 The clips fall onto the bottom of the chute represented by surface 112 of removable guide 100 (Figs. 8, 11 and 13). The pusher 16 advances as described earlier in the description and is so constructed that it pushes against the body portion 113 of the clip (Figs. 11 and 12) and not against the spring steel sub-base 114. The sub-base 114 of the clip 66 is of spring tempered material and only held in place on the clip base 96 by small ears 115 punched up enough to strike against slotted portions 116 of clip base 96. Cartridge retaining lugs 95 are formed out of each end of this sub-base 114. A slot 120 is milled out of the back of pusher 16 so as to allow sufficient clearance for retaining lugs 95 and not cause them to be bent when the pusher contacts the clip and pushes it over the ends of the cartridges. Should this spring piece 114 become dislodged from its proper position on clip 66 the cartridge retaining lugs would not be in their proper position for the final operation of the machine and damage to the clip would result.

Another clearance groove 122 (Fig. 11) is formed in the end nearest the pocket wheel of removable clip guide 100 so that the retaining lugs 95 on the clip may pass freely through it and not be damaged as the pocket wheel turns after the clip 66 has been pushed over the base ends of the cartridges (Fig. 13). A further clip guiding member 125 is provided on the leading end of pusher 16 (Figs. 11, 12, and 13) and it underlies the curved undercut portion 126 of removable guide 100 (Figs. 8 and 11) for further positive control of the clip 66 as it is pushed out of the guide 100 and onto the base ends of

the cartridges as shown in dotted lines in Fig. 11.

As the back or bottom 96 of the clip passes along between the base ends of the cartridges and the pressure plate 77 (Fig. 7) the spring member 114 resists the entrance of the cartridges because of its spring tempered character. Thus a substantial push by the pusher 16 is needed, requiring the described precautions to properly guide the clips so they will be secured to the base ends of the cartridges by the extractor grooves with the greatest precision, so that the machine may continue to run accurately and efficiently at a high rate of speed for maximum production. As will be seen in Fig. 15 the lower edges of the in-turned sides 92 of the clip engage the extractor grooves of the cartridges to hold them in the clip while the spring tempered sub-base number 114 continually presses the base ends of the five cartridges simultaneously against the lower edges of the in-turned clip sides to make a self sustaining unit or packet.

As the pusher 16 pushes one clip onto the base ends of the cartridges therefore engaging the extractor grooves of the cartridges simultaneously, the other clips ride on top of it and the one in direct contact with the pusher falls in front of it and is pushed from under the others by the pusher on its next forward stroke. The pusher will again return as the pocket wheel advances and on the next stroke forward, with the pocket wheel again at rest, another clip will be forwarded by the pusher and the rest of the clips will be held back and above the pusher as before (Fig. 13). With the clip in its proper place on the base ends of the cartridges where the pusher 16 left it, and with the pusher on its return stroke (Fig. 13), the pocket wheel will now turn step by step until the cartridges with their respective clips are delivered onto the discharge belt as completed units.

To make a complete unit, retaining lugs 95 must be bent upwards toward the cartridges as shown in Fig. 15. To accomplish this, inside and outside lug folders 130 and 131 respectively are provided through openings 132 and 133 respectively in cover 62. Bolts 134 and 135 secure lug folders 130 and 131 respectively to cover 62 for quick removal and replacement when signs of wear appear. As the pocket wheel 2 turns with the cartridges and their respective clips mounted upon them, lugs 95 on the ends of said clips come in contact with the inner and outer lug folders 130 and 131 respectively (Figs. 5 and 14). These stationary folders are shaped by grinding so as to bend the lugs 95 toward the cartridges at right angles to the clip base 96.

In Fig. 14 it will be noticed that dotted arrows 135' indicate the path of the clips, first from the pusher in against the spring pressure plate 77; then as the pocket wheel turns step by step they bear against the inner surface 76 of cover 62, past the lug folders 130 and 131 and on to the discharge station, being supported by the cartridges as they are carried along in the pockets of the pocket wheel to said station.

The housing 65 is cut away as at 137 to allow the cartridge assembly to fall onto the discharge belt 34 moving continuously below this opening. Should anything happen that may cause them to become lodged in the pocket, in pocket wheel 2, so as not to drop freely, a stationary cam 140 secured by bolts 141 to the housing 65 is positioned centrally of all pockets so that by the turning of the pocket wheel, the cartridges will definitely be cammed out of each pocket between

the guides 142 and onto the discharge belt 34 (Fig. 1) therefore assuring the clearance of said pockets for the entrance of more cartridges as the pockets come in alignment with the cartridge feed chutes again.

It will be understood that this machine will operate continuously as long as clips are supplied to the clip chute 85 and cartridges are supplied to the chutes 44 and 56. Suitable well known stop mechanism may be provided if desired for effecting an automatic stopping of the machine whenever there is a failure in the supply of either cartridges or clips.

What we claim is:

1. A loading machine for clips having a curved channeled base with cartridge retaining side lips and end lugs and a spring backing plate within the channel, comprising a radially slotted carrier rotatable on a horizontal axis, means for rotating the carrier step by step, a plurality of cartridge guides, mechanism for releasing a set of cartridges from each guide into alternate slots, a guide surrounding the carrier and a guide at the base of each slot coacting to hold the set closely assembled, one side of each slot being shouldered to engage the shoulders of the cartridges, a spring pressed block at one rest station of the carrier having a beveled portion to engage the bases of a set of cartridges simultaneously and hold them in engagement with said shoulders to bring their bases into alignment, a clip guide in alignment with the slot at said rest station, a magazine supplying clips to said guide, a plunger having a clip engaging end shaped to engage the ends of the base of the clip only, means to advance the plunger to remove a clip from the magazine and slide its channeled sides over the bases of the aligned cartridges in the slot, a pair of plow folders located adjacent the carrier and engageable with said end lugs to fold them against the walls of the end cartridges of each set, and an opening in said surrounding guide for the discharge of loaded clips therefrom.

2. A loading machine for clips having a curved channeled base with cartridge retaining side lips and end lugs and a spring backing plate within the channel, comprising a radially slotted carrier, means for rotating the carrier step by step, means for introducing a set of cartridges into each slot, a guide surrounding the carrier and a guide at the base of each slot coacting to hold the set closely assembled, one side of each slot being shouldered to engage the shoulders of the cartridges, a spring pressed block at one rest station of the carrier having a beveled portion to engage the bases of a set of cartridges simultaneously and hold them in engagement with said shoulders to bring their bases into alignment, a clip guide in alignment with the slot at said rest station, and a plunger operable to force a clip along the guide and between the cartridge bases and said spring pressed block with the side lips entering the extracting grooves of the cartridges.

3. A loading machine for clips having a curved channeled base with cartridge retaining side lips and end lugs and a spring backing plate within the channel, comprising a radially slotted carrier, means for rotating the carrier step by step, means for introducing a set of cartridges into each slot, a guide surrounding the carrier and a guide at the base of each slot coacting to hold the set closely assembled, one side of each slot being shouldered to engage the shoulders of the cartridges, a spring pressed block at one rest sta-

tion of the carrier having a beveled portion to engage the bases of a set of cartridges simultaneously and hold them in engagement with said shoulders to bring their bases into alignment, a clip guide in alignment with the slot at said rest station, a plunger operable to force a clip along the guide and between the cartridge bases and said spring pressed block with the side lips entering the extracting grooves of the cartridges, and means for turning the end lugs against the walls of the end cartridges of the set.

4. A loading machine for clips having a channeled base with cartridge retaining side lips, comprising means for holding a set of cartridges including guides engaging the shouldered portions of the cartridges and a spring pressed backing block engaging the bases of the cartridges to hold them in alignment, and means for forcing a clip between the bases of the cartridges and said block with the lips entering the extracting grooves of the cartridges.

5. A loading machine for clips, comprising a rotatable wheel having a plurality of circumferentially spaced pockets, means for intermittently rotating said wheel, two sets of mechanism for placing sets of cartridges alternately in successive pockets, and a single mechanism for applying clips to sets of cartridges in successive pockets.

6. A loading machine for channeled clips having side lips, comprising a wheel having a plurality of circumferentially spaced pockets, means for rotating the wheel step by step, one or more cartridge chutes having rails for guiding the cartridges by their sides, bases and shoulders to a point adjacent the periphery of the wheel, escapement mechanism for releasing a set of cartridges to pass into a pocket when the wheel is at rest, guide members associated with the wheel to guide the sets of cartridges by their sides and shoulders, and means operable at a rest station of the pockets for sliding a clip over the bases of the cartridges of a set.

7. A loading machine for channeled clips having side lips, comprising a wheel having a plurality of circumferentially spaced pockets, means for rotating the wheel step by step, one or more cartridge chutes having rails for guiding the cartridges by their sides, bases and shoulders to a point adjacent the periphery of the wheel, escapement mechanism for releasing a set of cartridges to pass into a pocket when the wheel is at rest, guide members associated with the wheel to guide the sets of cartridges by their sides and shoulders, a spring pressed backing block at a rest station of the pockets to engage the bases of

a set of cartridges, and means to slide a clip between the bases of the cartridges and said block with the channel embracing the bases and the side lips engaging the extracting groove of the cartridges.

5 8. A loading machine for channeled clips having side lips, and bendable end lugs, comprising a wheel having a plurality of circumferentially spaced pockets, means for rotating the wheel step by step, one or more cartridge chutes having rails for guiding the cartridges by their sides, bases and shoulders to a point adjacent the periphery of the wheel, escapement mechanism for releasing a set of cartridges to pass into a pocket when the wheel is at rest, guide members associated with the wheel to guide the sets of cartridges by their sides and shoulders, a spring pressed backing block at a rest station of the pockets to engage the bases of a set of cartridges, means to slide a clip between the bases of the cartridges and said block with the channel embracing the bases and the side lips engaging the extracting groove of the cartridges, and means operable to bend said end lugs against the end cartridges of each set.

25 9. A clip loading machine comprising a drum-like pocket wheel having a plurality of pockets therein, each pocket extending radially inward from an opening at the peripheral surface of said drum and also having a side opening at one side face of said drum, means for rotating said pocket wheel in a step by step manner, cartridge feed mechanism operating to fill each pocket through its peripheral opening with a set of cartridges having their bases in alignment and projecting from the side opening of said pocket, a pusher for sliding a clip over the projecting bases of the cartridges while in said pocket, and mechanism for bending lugs on the clip adjacent the cartridges at each end of the set to hold the set and the clip in assembled relation.

30 10. A clip loading machine comprising a drum-like pocket wheel having a plurality of pockets therein, each pocket extending radially inward from an opening at the peripheral surface of said drum and also having a side opening at one side face of said drum, means for rotating said pocket wheel in a step by step manner, cartridge feed mechanism operating to fill each pocket through its peripheral opening with a set of cartridges having their bases in alignment and projecting from the side opening of said pocket, and a pusher for sliding a clip over the projecting bases of the cartridges while in said pocket.

35 55 ELMER LOVELL SMITH.
CARLTON WETSEL.
